UNITED STATES PATENT OFFICE.

JAMES B. LADD, OF ARDMORE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL CASTING MACHINE.

Application filed September 13, 1921. Serial No. 500,331.

To all whom it may concern:

Be it known that I, JAMES B. LADD, a citizen of the United States of America, and resident of Ardmore, in the county of Montgomery and State of Pennsylvania, have invented a certain new and useful Improvement in Centrifugal Casting Machines, of which the following is a true and exact description, reference being had to the accompanying drawings, which form a part thereof.

My invention relates to centrifugal casting machines of the type described in the German patent to Briede, No. 242,307 issued January 4, 1912, that is to say a centrifugal casting machine comprising a relatively movable rotating mold and runner so operated that the molten metal flowing through the runner into the mold is delivered into the mold in a helical stream. The object of my invention is to generally improve the construction and efficiency of such a casting machine and particularly my object is, in the first place, to provide improved means for securing in the runner during the greater part of the casting operation a stream of molten metal of constant volume and velocity and with this object in view my invention consists in providing in connection with the mold and runner a pouring ladle or receptacle which remains in a substantially fixed position during the pouring of the metal, and from which the metal is poured into the runner and in which the metal is automatically maintained at a constant level and head.

Another object of my invention is to provide for the heating of the runner when it is withdrawn from the mold whereby it is prevented from cooling the iron poured into it and a more uniform temperature and fluidity of the iron is secured. The heating of the runner also reduces the amount of scull or dead iron left in the runner after each cast.

Another object of my invention is to provide an anti-frictional support whereby the runner can be supported within the mold. In the German patent above referred to the runner is provided near its outer end with a ring which rests upon the mold and serves to support the end of the runner therein. This ring also serves as a limit stop for the

flow of metal in the mold and as a means by which the casting is pushed out of the mold, and a further object of my invention is to provide an improved construction of such a ring and for its automatic attachment to and detachment from the runner and from the end of the mold whereby, as will be explained, it is made more practical and efficient.

Another object of my invention is to provide means for the ready adjustment of the inclination of the runner whereby the speed of the flow of metal therethrough and into the mold can be regulated.

Still another object of my invention is to provide means at the end of the runner whereby the longitudinal flow of the metal can be arrested and the metal delivered downward onto the mold.

Still another object of my invention is a construction of the runner and its supports so that the runner can be partly revolved on its supports and its contents dumped out and also the protection of the mechanism lying beneath the runner from contents dumped from the runner by interposing a cover plate beneath the runner and above said mechanism.

Still another feature of my invention is the combination with a casting machine of the type in question of a periscope by means of which the flow of metal into the mold can be observed from the point where the general operation of the mechanism is most readily controlled, and the special construction of this periscopic device so that it can be swung out of operative position to permit the free movement of the mold.

Still another feature of my invention is the provision of automatic mechanism whereby the motion of the mold with respect to the runner will begin at a definite time interval after the beginning of the delivery of metal into the runner so as to allow time for the metal to flow through the runner into the mold and to fill the end of the mold before the mold begins its longitudinal movement.

Another object of my invention is the provision of automatic mechanism whereby the speed of motion of the mold with reference to the runner can be slowed down after the flow of metal into the runner is stopped

and while the metal remaining in the runner is flowing into the mold in diminished quantity and at diminished speed. By properly adjusting the relative speed of movement of the mold and runner with reference to the diminishing flow of metal I utilize a larger amount of the metal coming from the ladle than has heretofore been practicable.

- 10 Another object of my invention is the provision of improved stop mechanism for arresting the relative movement of the mold with reference to the runner at both ends of its travel and at selectively different points.
- 15 A further object of my invention is the provision of supports for receiving the casting when pushed out of the mold and of automatic means whereby said supports are shifted out of the path of the mold during 20 the motion of the mold in the casting operation.

While the above are the leading objects of my invention there are other features which will be best understood as described in 25 connection with the drawings which illustrate a machine embodying my invention and in which—

- Figure 1 is a plan view of my improved machine.
- 30 Figure 2 is a side elevation of the machine with the mold in the position shown in Fig. 1.

Figure 3 is a similar side elevation with a mold shown in the position in which it is 35 moved over the runner.

- Figure 4 is a side elevation similar to that shown in Fig. 3 but with the mold and runner and the framing supporting the mold and runner, shown in vertical section along 40 the center of the machine.

Figure 5 is a sectional view similar to that of Fig. 4 with a mold shown retracted from the runner and the pouring and reservoir ladles also shown in section.

- 45 Figure 6 is a face view of the ladles and their supporting and actuating mechanism viewed as on the line 6—6 of Fig. 5.

Figure 7 is a view on an enlarged scale of a part of the mechanism shown in Figs. 50 1, 2 and 3.

- Figure 8 is a cross sectional view on the line 8—8 of Fig. 5.

Figure 9 is a cross sectional view on the line 9—9 of Fig. 5.

- 55 Figure 10 is a cross sectional view on the line 10—10 of Fig. 5.

Figure 11 is a cross sectional view on the line 11—11 of Fig. 5.

- Figure 12 an end view taken as on the 60 line 12—12 of Fig. 5.

Figure 13 is a view taken as on the line 13—13 of Fig. 4, looking toward the left.

- Figure 14 is a plan view of the end of the mold and of the end of the runner with the upper part of the water jacket casing

surrounding the mold removed and with the ring which is engaged by and which supports the end of the runner shown in section as is also the mechanism for automatically engaging the ring with the end of the mold 70 when the runner is withdrawn.

Figure 15 is a vertical sectional view through the end of the mold, its water jacket casing, the ring, and the runner, all shown in vertical central section. 75

Figure 16 is an end view of the appliances shown in Fig. 15, looking toward the left.

Figure 17 is an end view of the baffle plate secured to the end of the runner as 80 shown in Fig. 15.

Figure 18 is a sectional view of a detail of the construction shown in Figs. 14 and 15, drawn on an enlarged scale.

Figure 19 is a sectional elevation of the 85 end of the runner and baffle plate showing a slight modification in the construction shown in Figs. 15 and 16.

Figure 20 is an end view of the device 90 shown in Fig. 19.

Figure 21 is a detail shown partly in section of a preferential time escapement device which is not illustrated in the preceding figures by reason of their small size.

Figure 22 is an end view of the mechanism shown in Fig. 21. 95

Figure 23 is a sectional elevation of the mold, runner and modified ring supporting anti-frictional means in the relative positions which they occupy at the close of a 100 casting operation.

Figure 24 is a side elevation of the mechanism shown in Fig. 2 with the addition of the preferential device not illustrated in the former figures by means of which the motion 105 of the mold with reference to the runner can be slowed up at the close of the casting operation and while the runner is draining into the mold.

Figure 25 is an enlarged detail of the construction shown in Fig. 24, and 110

Figure 26 is a detail showing the mold and framework in sectional elevation and illustrating the arrangement of operative parts indicated in Figs. 10, 24 and 25. 115

A indicates the base on which the framing of the machine is supported. A', A', are the frames extending upward from the base A and on which the pouring and reservoir ladles are supported. B indicates the 120 framing supporting the mold and runner; B', B', tracks on which run the cylinders supporting the mold which, in the construction illustrated and by preference, constitutes the movable element of the relatively 125 movable parts made up of the mold and runner, although obviously, as in the case of the German patent above referred to, the runner can be moved backward and forward in a stationary mold. B², B², are brackets 130

extending out from the side of the frame B and serving as supports for the slideable stop rod H. B³, B³ and b³ are brackets supporting the rotatable rod or shaft indicated at N¹³. C indicates the lower and C' the upper section of the casing or water jacket surrounding the mold and supporting it in position. The lower section of the mold is provided with supporting wheels C² which run it over the tracks at B'. C³, C³, are supporting wheels for the mold journaled, as shown best in Fig. 11, on the inside of the casing. C⁴, C⁴, indicate piston rings located in annular grooves in the 10 end casing section C, C', fitting on the ends of the mold to prevent the escape of water from the water jacket. C⁵ is a pipe leading into one end of the casing section C and through which water is introduced into the 15 casing. As shown this pipe is provided with an extension C⁶ running parallel to the line of motion of the machine and passing through a stuffing box C⁹, Fig. 9, into a parallel pipe section indicated at C¹⁰, see 20 Fig. 8, and conveniently attached, as shown, to the cylinder F.

C⁶, best shown in Figs. 10, 15 and 23, is an upwardly extending chamber leading from the end of the casing section C' having, as shown, an open top and a drain pipe C⁷ by which the cooling water can freely flow off. D is the mold supported in the casing C, C', and of generally cylindrical form through, as illustrated and for use as 35 a bell mouth pipe mold, the mold is provided with a bell mouth D², see Figs. 4 and 5, against the end of which fits the removable head plate E² which may carry a bell core such as is indicated at D³. The rear 40 end of the mold is shown as provided with a gear indicated at D⁴ through which and the gear indicated at E' the mold is driven by a motor indicated at E.

As a means for moving the mold with 45 reference to the runner, any convenient mechanism can, of course, be employed but I prefer to use the cylinder, indicated at F, from the piston working in which, not shown in the drawings, extends a piston 50 rod F' secured to the rear end of the casing supporting the mold and which is preferably formed with an upwardly curved end as indicated at F³ for the purpose to be hereafter described. As a means for actuating the piston in the cylinder F fluid is introduced through the pipe G into a three-way valve, indicated at G', and through either of the pipes G² or G³ to the respective ends of the cylinder F. The cylinder 55 end not connected with the source of fluid under pressure is, through the valve, connected with the exhaust indicated at g and it will be understood that in the use of this device it is important that the fluid under 60 pressure should be kept under constant pres-

sure as uniformity of movement is exceedingly important in the operation of the machine. The valve G' is, as shown, actuated by a lever G⁴ and attached to this lever is a toothed segment G⁵, see Figs. 7 and 70 8, which engages a circular rack H' formed on or attached to a sliding rod H supported in the bearings B² provided with a handle H² by which it can be turned in its bearings and having at its left hand end a stop lever H³, see Fig. 10, which comes in contact with the finger h³ attached to the casing C', when the mold is moved to a predetermined position over to the right and by shifting the rod H and its toothed 75 rack H' moves the segment G⁵ of the valve G' to cut off the flow of fluid into the left hand end of the cylinder F. The stop lever H³ is, as shown in Fig. 10, broadened out at its end so that any rocking motion of the rod H will not move it out of operative 80 relationship to the finger h³. Also secured to the rod H are the stop levers H⁴, H⁵, which, as shown in Fig. 8, are set at an angle so that by turning the rod H either 85 90 one or the other can be brought into position to be engaged by the stop finger h³ and in this way the movement of the mold toward the runner can be increased to push the casting clear of the mold. 95

By preference I provide mechanism not only for arresting the movement of the mold as above described but also for slowing down its rate of movement towards the end of the casting operation, and I do this so that I 100 may cut off the supply of metal to the runner before the casting is completed and at the same time make available a large part or all of the metal remaining in the runner after the supply to it is cut off and the metal is 105 passing into the mold in reduced volume and velocity. This slowing up of the motion of the mold can be conveniently effected, as shown in Figs. 24, 25 and 26, by attaching to the end of the rod H a curved 110 lever H⁶ pivoted to the frame, as indicated at H⁷, and operated upon by a cam contacting surface, such as is indicated at h⁶, such cams being attached to the casing section C and operating on the lever H⁶ at the latter 115 part of the arresting motion of the casting and mold.

I is the runner which is, generally speaking, in the form of an open top trough with an upwardly inclined receiving end indicated at I' and preferably flared, as best shown in Fig. 13. The runner is formed with a rearwardly extending bearing indicated at I² and with a counterweight I³ and actuating lever i³. The bearing I² is supported on a standard I⁴ through a vertically movable support I⁸ which can be moved up and down by means of a bolt I⁹ and nut I¹⁰ so as to adjust the inclination of the 120 runner and thus regulate the speed with 125 130

which the metal flows through it. At the bottom of the delivery end of the runner the bearing surface I^5 is provided which, when the runner is retracted from the mold, as shown, for instance, in Fig. 15, rests on the roller I^{11} . The lower part of the end of the runner is also preferably beveled, as shown at I^6 , to enable it to freely enter the ring to be hereafter described.

10 In order to arrest the longitudinal motion of the metal running from the runner into the mold and deflect it downward to the mold I provide at the end of the runner a baffle plate or hood as indicated at I^7 , see Figs. 15 and 17, which may extend entirely beyond the side walls of the runner as shown in the above figures or may have extensions of the side wall, as indicated in Figs. 19 and 20, where i^7 indicates the extensions of the side walls of the runner. I^{12} I^{12} , are stiff springs secured to the sides of the runner and adapted to enter and frictionally engage the latches T when the runner is thrust into the ring K . I^{14} , I^{14} , are projections also secured to the sides of the runner, and which, when the ring K passes over the springs I^{12} , act to definitely locate the ring on the runner.

15 J is a ring fitting loosely in the mold D and provided with anti-friction ball races indicated at J' , and in this ring fits another ring K supported in the ring J by the balls indicated at K' and having preferably a flared end as indicated at K^2 . The outer portion of the ring J is formed with an annular recess, as indicated at J^2 , which recess, when the ring is in the position shown in Fig. 14, is indicated by fingers T' and the latches T having inwardly projecting fingers T^2 and attached to the rods T^3 which are pressed inwardly by springs indicated at T^4 , the arrangement being such that the ring is anchored in position at the end of the mold D until the latches are thrust back on the runner by the cams I^{13} which occurs after the end of the runner has entered the ring K and the springs I^{12} have taken a strong, frictional grip upon it.

20 Considering next the means used for heating the runner, L indicates a gas pipe pivotally supported on the brackets B^4 and from which extend upward pipes L' , L^2 , connecting with the pipes L^3 , L^4 , which extend under and over the runner as shown in Figs. 2 and 8; the pipes are in the position shown in full lines in Fig. 8 and they can be retracted, as shown in dotted lines, before the mold is being moved over the runner, and, at i^2 , I have indicated that the burner should extend under the lower side of the extension I' of the runner.

25 M , see, for instance, Fig. 15, indicates a drip trough to receive any metal draining from the runner when it is in the position shown in this figure. M^2 is a cover plate

supported on top of the framing B and between the runner and the mechanism lying beneath the runner.

30 Passing next to the part of the machine which has to do with the entry of a stream of molten metal into the runner, it is important that the metal passing to and through the runner during the greater part of the casting operation should travel in a stream of uniform section moving at a uniform velocity, and to secure these objects I provide a pouring ladle which remains in fixed position during pouring, having means for inducing and arresting the flow of metal therefrom into the runner and having means whereby a uniform level can be maintained in the ladle and a consequent uniform flow pressure secured. The special mechanism shown in the drawings and by which the above described results are secured consists of a bottom pour ladle N which is supported on a lever N' pivoted at U and provided with a counterweight N^2 . The arrangement being such that the ladle is held at a definite point with the lever arms N' practically horizontal when the ladle is charged with molten metal to its full capacity. As shown, the counterweight is provided with projecting pins n^2 over which extend slightly elongated loops R^2 of a limit stop consisting of a rod or rods R attached to the standard A' at R' . The ladle N should, for the best results, have a capacity several times that of the casting to be made in the rotary mold. The ladle is formed with a bottom pour orifice N^3 at its bottom and preferably with a cover n^4 in which is formed an opening N^4 for the reception of metal from a reservoir P and through which, as shown, extends the gas pipe N^6 by which gas can be introduced to maintain a flame on top of the metal. N^5 is a stopper by which the bottom pour orifice is opened and closed and this stopper, as shown, is connected to a vertically guided rod N^6 guided in the brackets N^7 , N^7 , and raised and lowered by means of the toggle levers N^8 , N^8 , which are actuated by the link N^9 , the bell crank lever N^{10} , the link N^{11} , the lever n^{11} and rock shaft N^{13} which is turned to raise or lower the stopper by the lever N^{12} and which is provided with another lever N^{14} which lies in operative relation to a cam plate N^{15} which is attached to the casing C , C' , as shown in Figs. 2 and 10, so that it contacts with the lever N^{14} during the latter part of the casting operation and rocks the shaft N^{13} in a direction to bring about the closing of the opening in the bottom pour ladle. By preference the rock shaft N^{13} is also provided with a crank arm n^{14} at its left hand end, as shown in Figs. 3, 21 and 22, so as to fill the time escapement device shown and described.

35 P is a reservoir ladle, as shown, of the bottom pour type having a stopper P' for open-

ing and closing its delivery orifice and this stopper is connected by a guide rod P^2 and a link P^3 attached at its lower end to a lever arm n' attached to and moving with the 5 levers N' .

While I have in mind to provide automatic means for regulating the starting of the longitudinal movement of the mold, it is highly desirable that the flow of metal 10 into the end of the mold at the beginning of the casting operation should be observed and the motion of the mold when necessary controlled so as to secure just the right amount of metal for the formation of the 15 bell or end of the mold before longitudinal motion is imparted to the mold and to enable an operator situated at the head of the machine to judge the flow of metal, I provide my machine with periscope consisting of 20 a tube Q pivotally supported in the standards Q^3 so that it may be regulated, having a sight glass indicated at Q' at its right hand end and an arm indicated at Q^2 so arranged that when turned down it will enable 25 the operator to look directly into the left hand end of the mold when the mold is in the position shown in Fig. 4. The rotatable periscope is provided with a lever arm Q^4 by which it can be rocked into and out of 30 operative position and with a counterweight Q^5 by which it is balanced.

It is desirable that rests or supports should be provided to receive the cast pipe when it is pushed out of the mold. These supports 35 must also be retracted to clear the mold when it is moved toward the left and I provide for this requirement by means of the rock shafts S , S' , best shown in Figs. 4, 5, 11 and 12, which are supported in bearings 40 in the frame B and provided with torsion springs S' which tend to move them in one direction. To the shafts S I secure the hubs S^2 and supports S^3 which, by the action of the springs, are normally held in the position 45 indicated in Fig. 4 but which, when the mold moves toward the left, are pressed down by the curved end F^3 of the rod F' and held below the mold in the position shown in Fig. 5.

50 To describe now the operation of my improved machine, and assuming the parts to be initially in the position shown in Figs. 2 and 5, the first thing to be done is to heat the runner to a sufficiently high degree to avoid the risk of chilling the metal which is about 55 to be run into it. This is accomplished by means of the burners L^3 , L^4 , which at this time are brought to the position shown in Fig. 8, and which are retracted to the position 60 shown in dotted lines before the mold is moved forward over the runner and the next thing to be done is to move the mold toward the right until it reaches the position shown in Fig. 4. This is readily accomplished by moving the lever G^4 of the valve 65

G' so as to pass the fluid under pressure through the pipe G^3 to the left hand end of the cylinder F , permitting the fluid in the right hand side of the cylinder to pass out through the pipe g at the beginning of the 70 motion of the mold toward the right. The ring J is held in the mouth of the mold as shown in Fig. 14, by the jaw T' of the latches T and the ring, together with its actuated center ring, moves over the end of the 75 runner I , the spring I^{12} being pressed against the inner face of the ring K so as to take a strong, frictional grip upon it. Continued motion of the mold brings the fingers T^2 of the latch T into contact with 80 the cams I^{13} pushing apart the latches T until the jaws T' release their hold on the ring J after which the rings remain stationary on the end of the runner and support the end 85 of the runner, the ring K being, of course, stationary with regard to rotation and the ring J which is in frictional contact with the rotating mold D , rotating with it. At the end of this movement the parts are in the 90 position indicated in Fig. 4 and the periscope is turned from the position it has heretofore occupied, that shown in Fig. 5, to its operative position, that shown in Fig. 4.

The operator next turns the rock shaft N^{13} by means of the lever N^{12} and through 95 the lever n^{11} , link N^{11} , bell-crank N^{10} , rod N^9 forces the toggle joint links N^8 into a vertical line and thus lifts the guide rod N^6 and the stopper N^5 and opens the bottom pour channel in the ladle to its full extent. 100 It will be understood that before beginning to pour from the ladle N the ladle is charged to its full maximum extent and is counterbalanced by the counterbalance weight N^2 . As metal flows out of the ladle it is forced 105 upward by the counterbalance N^2 moving the lever arm N' upwardly and, through the rod P^3 , the guide rod P^2 raises the stopper P' in the bottom pour reservoir P . The extent to which the pouring orifice in the 110 reservoir P is open depends on the extent of the upward motion of the ladle N and it will readily be understood that the device I have illustrated can and will have the 115 effect of maintaining a practically constant level of melted metal in the ladle N .

It will be understood, of course, that it takes an appreciable interval of time for the stream of metal coming from the ladle N to pass through the runner I into the mold 120 and it will also be obvious that when a bell mouth pipe is being cast it will take also an appreciable time to fill the bell end of the mold, and it is not until the metal is in full flow into the mold and the bell end 125 filled, that the travel of the mold toward the left should begin. The flow of metal into the mold of course can be observed through the periscope and the valve lever G^4 turned to operate the valve to a position to start 130

the mold toward the left just at the proper time, but while manual control cannot perhaps be entirely avoided, it is, where the uniform flow of metal is provided for as I provide for it, practical to provide means for automatically starting the mold in longitudinal motion and at the proper time. Such a means I have shown in Figs. 3, 21 and 22, whereby rocking of the shaft N^{13} through the lever arm n^{14} opens the valve O^3 , admitting fluid pressure to the right side of the time escapement cylinder O^7 with the result of moving the piston O^8 and rod O^9 backward with regulated speed until the rod O^9 clears the lever arm O^{10} and the lever arm O^{12} actuating on the stop O^{13} on the rod H shifts this rod toward the right and through the rack H' and segment G^5 shifts the valve G' to a position to start the left hand movement of the mold. Obviously, by throttling the exhaust O^6 the speed of movement of the time escapement cylinder can be regulated.

As the mold continues its motion toward the left with uniform speed and the metal is delivered into it from the end of the runner in uniform volume and velocity the metal is laid in the revolving mold in a helix-like coil, the adjacent coils fusing freely together but not having time to flow laterally to any great extent. In this connection it will be noted that the provision of the baffle plate I^7 is important as tending to check the longitudinal motion of the metal at the end of the runner and result in its flowing downward practically at right angles to the surface of the mold, so that so far as the momentum of the metal is concerned there is but little tendency to impart a longitudinal flow to it when it reaches the mold.

In the construction illustrated I use the ring J as the means of pushing the cast pipe out of the mold and to properly perform the function it must during the right hand movement of the mold approach more closely the end of the mold than during the pouring operation or it may even be best to have it partly clear the end of the mold. To provide for the movement I secure to rod H the two angling fingers H^4 , H^5 , either of which can be turned to position to contact with finger h^3 by turning the rod H . When either finger H^4 or H^5 contacts with finger h^3 the rod H is moved toward the right and through the rack H' and segment G^5 turns the valve G' to a position to cut off the flow of pressure fluid to the cylinder F and bring the mold to a rest in the desired position with reference to ring J .

It will be obvious that the fingers H^3 , H^4 , and H^5 should all be adjustable lengthwise on the rod H so that the motion of the mold can be arrested at selective points. Ob-

viously the motion of the mold toward the left is arrested through the contact of the stop finger h^3 with the lever H^8 attached at the left hand end of the rod H and operating to close the valve admitting pressure fluid.

It is obviously desirable to provide automatic means for cutting off the flow of molten metal from the ladle N at a proper time and this is effected in my machine by the action of the cam N^{15} on the lever N^{14} , see Fig. 10, the pressing outward of the lever N^{14} rocking the shaft N^{13} in a direction to draw the toggle levers N^8 , N^9 , outward, as shown in Fig. 6, and cut off the flow from the ladle.

When the flow of the metal from the ladle is cut off before the casting has been completed it is obvious that the metal remaining in the runner will flow into the mold with decreasing volume and velocity and consequently the end of the casting will be thinner if the rate of motion of the mold remains the same. It is, therefore, advisable to slow up the motion of the mold after the flow of metal from the ladle has ceased at a rate corresponding to the decreasing rate at which metal from the runner flows into the mold and this I provide for by securing to the mold casing a cam h^6 operating upon a curved lever H^6 pivoted at H^7 and secured, as shown in Figs. 24 and 25, to the end of the rod H . It will, of course, be evident that as the rod H is gradually drawn toward the left it will effect a gradual closing of the valve G' and a gradual diminution of the pressure fluid admitted to the cylinder F and this can readily be regulated.

The casting being complete it is next necessary to extract the casting from the mold and in my machine this is accomplished by moving the mold toward the right with the result that the ring J presses against the end of the casting, as shown in Fig. 23, and being held in fixed position on the runner either by direct attachment to it, as shown in Fig. 23, or by detachable means such as are shown in Figs. 14 and 15, holds the casting stationary while the mold moves over it and at the end of the motion of the mold the casting is entirely free thereof and in my construction is received on the supports S^8 , as shown in Fig. 4, these supports rising to receive the casting as the mold moves from above them and being retracted on the reverse movement of the mold as I have already described.

After the extraction of the casting the mold is again moved toward the left until it is clear of the runner and the runner is then turned partly over to discharge any metal or slag material remaining in it and to facilitate the removal of any adhering metal and then turned back to operative

position, heated by the gas burners and the operation goes on as before, and it will be observed that I provide the cover M^2 and other appliances described to prevent the 5 cleanings from the runner falling into the space between the sides of the frame B.

Having now described my invention, what I claim as new and desire to secure by Letters Patent, is:

10 1. In a centrifugal casting machine comprising a rotatable mold, a runner for delivering molten metal to the mold and means for imparting a relative longitudinal motion to the runner and mold, the combination therewith of a ladle stationary during pouring for delivering a stream of molten metal to the runner and means for maintaining a substantially uniform level of metal in the ladle whereby a constant 15 volume and velocity is maintained in the stream issuing therefrom.

2. In a centrifugal casting machine comprising a rotatable mold, a runner for delivering molten metal to the mold, and means for imparting a relative longitudinal motion to the runner and mold, the combination therewith of a ladle stationary during pouring for delivering a stream of molten metal to the runner, said ladle having a holding capacity several times that of the volume of the casting to be made and means for maintaining a substantially uniform level of metal in the ladle whereby a constant volume and velocity is maintained in the stream issuing therefrom.

3. In a centrifugal casting machine comprising a rotatable mold, a runner for delivering molten metal to the mold and means for imparting a relative longitudinal motion to the runner and mold, the combination therewith of a ladle stationary during pouring for delivering a stream of molten metal to the runner and means actuated by variations in the weight of metal 40 in the ladle for maintaining a substantially uniform level of metal in the ladle whereby a constant volume and velocity is maintained in the stream issuing therefrom.

4. In a centrifugal casting machine comprising a rotatable mold, a runner for delivering molten metal to the mold and means for imparting a relative longitudinal motion to the runner and mold, the combination therewith of a bottom pour ladle 45 for delivering a stream of molten metal to the runner and means for maintaining a substantially uniform level of metal in the ladle whereby a constant volume and velocity is maintained in the stream issuing therefrom.

5. In a centrifugal casting machine comprising a rotatable mold, a runner for delivering molten metal to the mold and means for imparting a relative longitudinal motion to the runner and mold, the combi-

nation therewith of a ladle for delivering a stream of molten metal to the runner, means for supporting said ladle whereby it is permitted to move up and down with variations in its weight, a reservoir for 70 molten metal arranged to deliver its metal to the said ladle and means for controlling the flow of metal from the reservoir to the ladle actuated by the movements of the ladle so as to maintain a constant level of 75 metal in the ladle.

6. In a centrifugal casting machine comprising a rotatable mold, a runner for delivering molten metal to the mold and means for imparting a relative longitudinal 80 motion to the runner and mold, the combination therewith of means for heating the runner located to operate when the runner is withdrawn from the mold.

7. In a centrifugal casting machine comprising a rotatable mold, a runner for delivering molten metal to the mold and means for imparting a relative longitudinal motion to the runner and mold, the combination therewith of means for heating the 90 runner, comprising retractable gas burners.

8. In a centrifugal casting machine comprising a rotatable mold, a runner for delivering molten metal to the mold and means for imparting a relative longitudinal 95 motion to the runner and mold, the combination therewith of a ring slidable in the mold and serving as a support for the delivery end of the runner, and anti-friction means interposed between the ring and 100 runner.

9. In a centrifugal casting machine comprising a rotatable mold, a runner for delivering molten metal to the mold and means for imparting a relative longitudinal 105 motion to the runner and mold, the combination therewith of a ring slidable in the mold and serving as a support for the delivery end of the runner, a second ring revolvable within the first ring and means 110 for securing the second ring in the runner.

10. In a centrifugal casting machine comprising a rotatable mold, a runner for delivering molten metal to the mold and means for imparting a relative longitudinal 115 motion to the runner and mold, the combination therewith of a ring slidable in the mold and serving as a support for the delivery end of the runner, anti-friction means interposed between the ring and runner, means whereby said ring is engaged by the runner during its relative backward and forward motion with relation to the mold and means for disengaging the ring from the runner and holding the ring within the end of the mold. 120

11. In a centrifugal casting machine comprising a rotatable mold, an open ended 130

runner for delivering molten metal to the mold and means for imparting a relative longitudinal motion to the runner and mold, the improvement which consists in making the runner rotatable on its supports so that any residue contained therein can be dumped when the runner is withdrawn from the mold.

12. In a centrifugal casting machine comprising a rotatable mold, an open ended runner for delivering molten metal to the mold and means for imparting a relative longitudinal motion to the runner and mold, the improvement which consists of means for independently adjusting the inclination of the runner.

13. In a centrifugal casting machine a relatively movable mold and runner in combination with power mechanism for moving the same, means for stopping the moving element at the designed limits of its movements comprising a stop engaged when the runner is fully without the mold and two stops adjustable so that one or the other is engaged as the runner moves into the mold and motion is arrested at selective points.

14. In a centrifugal casting machine a relatively movable mold and runner in combination with power mechanism for moving the same and means for varying the speed of motion of the relatively moving elements whereby the speed of motion of the positively movable element is varied at definite points of its path of motion.

15. In a centrifugal casting machine having a relatively movable mold and runner and power mechanism for moving the same, means for feeding molten metal to the runner, means for inducing and stopping the flow of metal to the runner and automatic means for actuating said flow controlling device to stop the flow of metal when the moving element reaches a determined point.

16. In a centrifugal casting machine having a relatively movable mold and runner and power mechanism for moving the same, means for controlling the motion of said power mechanism, means for feeding molten metal to the runner, means for inducing and stopping the flow of metal to the runner and means for causing the power mechanism to start moving the mold and

runner relative to each other at a definite time after the flow of metal to the runner begins.

17. In a centrifugal casting machine comprising a relatively movable mold and runner the combination therewith of means for feeding a uniform stream of metal to the runner, automatic means for cutting off the flow of metal to the runner, means for moving the moving element and means for slowing down the motion of said moving element after the flow of metal to the runner is cut off and while the metal in the runner is flowing therefrom in a diminishing stream.

18. In a centrifugal casting machine comprising a longitudinally movable mold and a stationary runner, supports for the casting arranged to receive the casting when the mold is over the runner and automatic means for moving the supports out of the way of the mold when it is moved away from the runner.

19. In a centrifugal pipe casting machine comprising a runner fixed in position, means for feeding molten metal to the runner, a longitudinally movable pipe mold and control mechanism for regulating the movements of the mold, the combination therewith of a periscope having a sight opening located adjacent to the control mechanism and its observing end directed into the distant end of the mold.

20. In a centrifugal casting machine comprising a relatively movable mold and runner the combination therewith of a periscope whereby the flow of metal into the mold can be observed, said periscope being supported so that it can be moved to clear the mold.

21. In a centrifugal casting machine comprising a longitudinally stationary runner, a longitudinally movable mold and mechanism for moving the mold located beneath the runner, a cover plate located between the runner and said mechanism.

22. In a centrifugal casting machine comprising a rotatable but longitudinally stationary runner, a longitudinally movable mold and mechanism for moving the mold located beneath the runner, a cover plate located between the runner and said mechanism.
